FÉLICIEN DURANT, OF BRUSSELS, BELGIUM.

BRASS WIND INSTRUMENT.

1,205,868.

Specification of Letters Patent.

Patented Nov. 21, 1916.

Application filed June 10, 1911. Serial No. 632,579.

To all whom it may concern:

Be it known that I, FÉLICIEN DURANT, subject of the King of the Belgians, residing at 149, Rue de la Victoire, Brussels, Belgium, have invented certain new and useful Improvements in Brass Wind Instruments, of which the following is a specification.

Wind instruments with tone raising and tone lowering valves for the production of the chromatic scale have been disclosed and in one form three tone lowering and three tone raising valves are shown upon the drawing of such an instrument.

Now the subject matter of the present invention is such an instrument with three tone raising and three tone lowering valves, with special intervals so that by the first tone raising valve the instrument is raised by one tone above the open column of air, by the second tone raising valve in combination with the first the instrument is raised by a further tone, and by the third in combination with the first and second by still another half tone. Such an instrument has the special advantage over others, for instance, an instrument with note changes by a half, a whole, one and a half, or by a half, one or two tones, that the crooks of the tone raising valves are shorter.

The drawing represents one form of carrying out the invention.

The instrument shown is a horn in F, which, used without piston, has a theoretical length of 3939 mm., as every other horn in F, but it has the peculiarity that the slides *a b c; d e f; g h i*, corresponding respectively to the pistons 4, 5 and 6, form part of this length of 3939 mm. and that these pistons are for the purpose of shortening the column of air, being combined among themselves in different ways.

The pistons 1, 2 and 3 are the ordinary descending pistons, lowering the column of air respectively by one tone, one-half tone, and two tones. The third piston might be descendant by one-and-one-half tones as it is actually in many instruments, but that arrangement causes the loss of important combinations of corrections.

The pistons 4, 5 and 6 are ascendant and combinable; the 4th raises the instrument by one tone by cutting out the slides *a b c*; the 6th piston raises the instrument by one-half tone over the two preceding, that is to say that the simultaneous use of pistons 4,

5 and 6 cuts out the three slides *a b c, d e f, g h i* of the column of air. The instrument being in F, the 4th piston gives the fundamental G; the pistons 4 and 5 combined give the fundamental A, and pistons 4, 5 and 6 combined give the fundamental B flat.

The instrument thus constructed is omnintonic, that is it gives twelve distinct fundamentals, which follow each other uniformly, within an octave, in half tones. These twelve fundamentals are purely produced by the fingering in descending chromatic sequence given in the table below.

In case of necessity a thirteenth position can be obtained by the use of the valves 1, 2, 3, but this gives an excessively high nominal A.

In the table below is also given a statement of the lengths of the horn, as they are shown by the various combinations of the fingering for a horn whose open column stands at F.

Position.	Real tone.	Valves used.	Required lengths. mm.	Lengths obtained. mm.	80
First	B flat	4, 5, 6	2950	2950	
Second	A	4, 5	3126	3126	
Third	A flat	4, 6	3313	3333	
Fourth	G	4	3509	3509	
Fifth	G flat	2, 4	3718	3744	85
Sixth	F	0	3939	3939	
Seventh	E	2	4174	4174	
Eighth	E flat	1	4422	4422	
Ninth	D	1, 2, 3, 4, 5, 6	4684	4692	
Tenth	D flat	3	4963	4963	
Eleventh	C	1, 2, 3, 4	5258	5251	
Twelfth	B	1, 2, 3, 6	5571	5505	

The changes in length due to each of the valves for an instrument in F are as follows:—Tone lowering valves: first, 483 mm.; second, 235 mm.; third, 1024 mm. Tone raising valves: fourth, 430 mm.; fifth, 383 mm.; sixth, 176 mm.

I claim:—

1. A wind instrument having three tone raising valves, and three tone lowering valves and corresponding crooks controlled by said valves respectively, the first tone raising valve raising the pitch of the open column by one tone, the second and first tone raising valves combined raising the pitch two tones, and the third in combination with the first and second raising the pitch by still an additional half tone.

2. A wind instrument having three tone raising valves, and three tone lowering valves and corresponding crooks controlled

by said valves respectively, the first tone raising valve raising the pitch of the open column by one tone, the second and first tone raising valves combined raising the pitch two tones, and the third in combination with the first and second raising the pitch by still an additional half tone, the tone lowering valves lowering the pitch by

one tone, one-half tone and two-tones respectively.

In testimony whereof I affix my signature in presence of two witnesses.

FÉLICIEN DURANT.
